UNITED STATES PATENT OFFICE.

SIDNEY U. BARR, OF BROOKLYN, NEW YORK.

WINDOW.

Application filed June 4, 1920. Serial No. 386,615.

To all whom it may concern:

Be it known that I, SIDNEY U. BARR, a citizen of the United States, and a resident of the city of New York, borough of Brooklyn, 5 in the county of Kings and State of New York, have invented a new and Improved Window, of which the following is a full, clear, and exact description.

The object of the invention is to provide 10 a new and improved window arranged to permit of easily and conveniently moving the sashes into open or closed position and to render the window completely dust and air and water tight when the sashes are 15 closed.

Another object is to prevent rattling of the lower sash in whatever position it may be in.

Another object is to prevent the lower 20 sash from being raised from the outside.

Another object is to permit convenient access to the overhead pulleys from inside of the window frame to allow of removing a pulley and replacing it as well as the chains 25 and weights without removing any part of the window frame or the sashes.

Another object is to reinforce the window sashes at the corner with a view to render practically each sash as if made of one piece.

30 Another object is to permit of applying the outer staff or scribe molding to the window frame with a view to draw or fit the same into any irregularities of the stone or brickwork of the building to render the 35 window frame air-tight and water-tight in the window opening.

With these and other objects in view, the invention consists of certain novel features of construction as hereinafter shown and described and then specifically pointed out in the claims.

A practical embodiment of the invention is represented in the accompanying drawings forming a part of this specification, in 45 which similar characters of reference indicate corresponding parts in all the views.

Figure 1 is an inner face view of the improved window with the sashes in closed and locked position and with parts broken out 50 and parts shown in sections;

Figure 2 is an enlarged transverse section of the same on the line 2—2 of Figure 1;

Figure 3 is an enlarged face view of one corner of sash frame;

55 Figure 4 is a sectional face view of the same on the line 4—4 of Figure 5;

Figure 5 is a cross section of the same on the line 5—5 of Figure 3;

Figure 6 is a perspective view of the reinforcing angular knee for a sash frame 60 corner;

Figure 7 is an enlarged cross section of the improved window with the lower and upper sashes in unlocked open positions;

Figure 8 is a sectional plan view of the 65 improved window on the line 8—8 of Figure 2;

Figure 9 is a similar view of the improved window at the lower sash, the section being on the line 9—9 of Figure 1, the lower sash 70 being in closed and locked position;

Figure 10 is a similar view of the same with the lower sash in released position;

Figure 11 is a sectional plan view on one side of the window frame on the line 11—11 75 of Figure 1;

Figure 12 is an enlarged plan view of the upper corner of the window casing and with one of the pulleys and its housing in position and the other removed;

Figure 13 is a sectional side elevation of the same on the line 13—13 of Figure 12; and

Figure 14 is a sectional plan view of one side of a modified form of the window frame 85 with the upper sash in position.

The improved window in its general construction consists of a lower sash 10, an upper sash 11 and a window frame comprising a sill 12, side bars or jambs 13, 13 and 90 a top crossbar 14. The side bars 13 of the window frame are provided with inner beads

20, outer beads 21 and parting strips 22 to form vertical guideways for the sashes 10 and 11 to slide in. The beads 20 are fastened to the side bars 13 by screws 23, and screws 24 serve to fasten the parting strips 22 to the

said side bars while the outer beads 21 are preferably formed integral with the side bars 13, as will be readily understood by reference to Figures 8, 9, 10 and 11. A front stop bead 25 is secured by screws 26 to the sill 12 of the window frame, and a similar stop bead 27 is fastened by screws 28 to the top crossbar 14 of the window frame, as 95 will be readily understood by reference to Figure 2. The top crossbar 14 is provided at its under side with an outer integral stop bead 29 forming a continuation of the outer side stop beads 21 (see Figure 2). A parting strip 30 is attached to the under side of the top crossbar 14 by screws 31 (see Figure

80

85

90

95

100

105

110

2) and forms a continuation of the parting strips 22 attached to the side bars 13 of the window frame. The parting strips 22 are set in recesses 32 formed in the side bars 13 of the window frame, and the top parting strip 30 is set in a similar recess 33 formed in the under side of the top crossbar 14 thus securely holding the parting strips in position on the window frame.

10 The lower sash 10 is hung on chains or other flexible connections 40 extending upward and passing over pulleys 41 mounted in housings 42 attached to the top cross-bar 14 of the window frame, as hereinafter more fully explained, and the chains 40 support sash weights 43 to counterbalance the lower sash 10 with a view to permit the easy raising and lowering of the sash 10. The upper sash 11 is hung on chains or other flexible connections 45 extending over pulleys 46 journaled in housings 47 attached to the top crossbar 14 of the window frame, and the said flexible connections 45 support sash weights 48 for counterbalancing the upper sash 11 to permit of conveniently lowering or raising the same. The suspension means for the lower sash 10 as described is arranged to hold this lower sash 10 inwardly against the stop beads 20 at the time the sash is in an open position, and the suspension means for the upper sash 11 as described and shown is arranged to hold the upper sash outwardly against the outer stop beads 21 at the time the upper sash is in open position, as will be readily understood by reference to Figure 7. The lower and upper sashes 10 and 11 when in open position (see Figure 7) are out of engagement or contact with the parting strips 22 and hence the sashes 10 and 11 can freely slide up and down in their guideways on the window frame thus requiring comparatively little exertion on the part of the operator to move the sashes up or down. The stop beads 20 are provided at their lower ends at the back with wedges 50 inclined downwardly and outwardly (see Figures 2 and 7), and the wedges 50 are engaged by the lower sash 10 at the time the latter is moved into a closed position thus forcing the lower portion of the lower sash 10 outward against the parting strips 22 (see Figure 2). The front faces of the upper ends of the outer stop beads 22 are provided with similar wedges 51 inclined upwardly and inwardly as plainly shown in Figures 2 and 7, and these wedges 51 are engaged by the upper ends of the upper sash 11 when the latter is moved into a closed position thus moving the upper portion of the upper sash 11 against the back of the parting strips 22, 30 (see Figure 2). The meeting rails 55 and 56 of the lower and upper sashes 10 and 11 are provided with interlocking members 57, 58 engaging one the other on moving the

sashes 10 and 11 into closed position (see Figure 2). The interlocking member 57 is provided with a cushion or packing 59, preferably in the form of a piece of rubber tubing, adapted to be engaged at the under side 70 by the interlocking member 58 so as to form an exceedingly tight joint between the meeting rails. On the top of the meeting rail 55 is mounted a drawing and locking device 60 having a movable member 61 adapted to engage a keeper 62 attached to the meeting rail 56 of the upper sash 11 to draw the meeting rails 55, 56 towards and in contact with each other to form a tight metallic joint, at the same time moving the upper 80 portion of the lower sash 10 against the front face of the parting strips 22 and moving the lower portion of the upper sash 11 against the rear or back faces of the said parting strips 22. From the foregoing it 85 will be seen that by the arrangement described the sashes 10 and 11 when in open position are held freely suspended by their suspension means and when moved into closed position the sashes form exceedingly tight 90 joints with the window frame and at the meeting rails 55 and 56 to render the window air, dust and waterproof tight. It is understood that the wedges 50, 51 and the drawing and locking device 60 coact to produce the desired result.

In order to reduce friction to a minimum in sliding the freely suspended sashes 10 and 11 up or down on the window frame, the side bars or jambs 13 are provided at the 100 guideways for the sashes 10 and 11 with integral ribs 70, 71 extending throughout the height of the guideways and projecting into the same, and being engaged by the corresponding sides of the sashes 10 and 11 practically with line contacts thus permitting easy up and down sliding movement of the sashes 10 and 11 (see Figures 8, 9 and 10).

In order to form an exceedingly tight joint between the lower window sash 10 and the parting strips 22 the latter are provided at their front faces with recesses 75 in which are secured cushions or packings 76 (see Figures 9 and 10) preferably in the form of rubber tubes projecting from the faces of the parting strips and engaging grooves 77 formed in the rear faces of the stiles 80 of the lower sash 10 and which stiles are connected with each other at the top by the meeting rail 55 and at the bottom by the bottom rail 81. The rear faces of the parting strips 22 are provided in their upper portions with recesses 85 in which are secured cushions or packings 86 similar to the cushions 76 and adapted to engage recesses 87 formed in the front faces of the stiles 90 of the upper sash 11, and which stiles 90 are connected with each other at their lower ends by the meeting rail 56 and at their upper ends by the top rail 91, 130

The bottom rail 81 of the lower sash 10 is provided at its under side with a recess 95 in which is fastened a cushion or packing 96, preferably in the form of a rubber tube, 5 adapted to be seated on a shoulder 97 formed in the sill 12 (see Figure 2). The top of the top rail 91 of the upper sash 11 is provided with a recess 98 in which is secured a cushion 99 adapted to make contact with 10 a rib 100 formed integrally in the top cross-bar 14 of the window frame. By the arrangement described the cushions 96 and 99 form tight joints between the bottom and top rails 81 and 91 of the lower and upper 15 sashes 10 and 11 with the sill 12 and the top crossbar 14 of the window frame at the time the said sashes are in closed position. The relation between the wedges, the cushion 99 and the rib 100 is such that when the 20 upper sash 11 is moved into closed position the cushion 99 touches the rib 100 to make a tight joint without, however, indenting or crushing the cushion.

In order to prevent the lower sash 10 from 25 rattling and to lock it in place when in raised position, use is made of sash binders 110 pivoted at 111 on the inner faces of the stiles 80 of the lower sash 10, and the said binders are provided with canis 112 adapted 30 to pass between the stop beads 20 and the inner faces of the stiles 80 to clamp the rear faces of the said stiles against the parting strips 22 (see Figure 9) thus holding the lower sash locked when in raised position 35 to prevent rattling of such sash or raising it from the outside. In order to permit convenient raising and lowering of the lower sash 10 the bottom rail 81 is provided at the inner face with the usual handholds 40 115 (see Figure 1).

The sash frames of the lower and upper sashes 10 and 11 are practically alike in construction and hence it suffices to describe but one in detail, special reference being had 45 to Figures 3, 4, 5 and 6, which show the construction of the upper sash frame. The stiles 90 of the upper sash 11, the meeting rail 56 and the top rail 91 are made tubular and the adjacent ends are mitered and 50 united by an angular kneepiece 120 having a vertical arm 121 and a horizontal arm 122, of which the vertical arm 121 extends into the stile 90 and the horizontal arm 122 extends into the corresponding end of the top 55 rail 91 or the meeting rail 56. The arms 121 and 122 are in cross-section the same as the inner cross sections of the stiles 90, the top rail 91 and the meeting rail 56. The kneepiece 120 is provided at the arm 121 60 with a vertical opening 123 for the passage of the corresponding chain 45 or 40. It is understood that the end of this chain extends through an opening 124 formed in the outer wall of the corresponding stile 90 65 or 80 and is secured to the corresponding

stile by a cotter pin or other suitable fastening device (not shown). The kneepiece 120 is provided with shoulders 130 and 131, of which the shoulder 130 is adapted to be engaged by the corresponding rail 91 or 56, 70 and the shoulder 131 by the corresponding stile 90. The parts are brazed together after the kneepiece 120 is inserted in the stiles and rails so as to render the sash frame exceedingly strong and durable and practically the same as if it were made of one single piece of metal or other material.

The side bars or jambs 13 of the window frame are provided with front and rear flanges 140 and 141, and similar flanges 142 80 and 143 are formed on the top crossbar 14, and the adjacent ends of the side bars 13 and the top crossbar 14 are connected with each other by angular kneepieces 150 which also serve to removably support the housings 42 and 47 of the pulleys 41 and 46 (see Figures 1, 12 and 13). Each of the kneepieces 150 consists of a vertical member 151 and a horizontal member 152 and the said members are provided with front flanges 90 153, 154 and rear flanges 155, 156 fitting against the corresponding flanges 140, 142 and 141, 143 of the side bars 13 and the top crossbar 14, as above mentioned. The flanges are fastened together by screws or 95 other fastening devices 157 to readily connect the side bars 13 with the top crossbar 14. Each of the pulley housings 42, 47 is provided with a base 160 extending in registering cut-out portions 161, 162, of which 100 the cut-out portion 161 is formed in the horizontal member 152 of the kneepiece 150 while the cut-out portion 162 is formed in the top crossbar 14. The inner end of each base 160 extends under a raised crosspiece 105 163 formed integrally at the inner portion of the horizontal member 152 of the kneepiece 150. A screw 164 engages the base 160 and the cross piece 163 to fasten the base in place, the head of the screw being on the 110 under side of the base 160 to permit access to the screw for removing the same whenever it is desired to remove the corresponding housing 42 or 47 from the window frame. The sides of each housing 42 and 47 have 115 their bottom portions provided with notches 165 seated on brackets 166 formed integrally with the vertical member 151 of the kneepiece 150 thus supporting the housing and holding the same in position aided by the 120 corresponding screw 164. The upper portions of the kneepiece 151 and the side bars 13 are provided with registering cut-out portions 167, 168 for the passage of the corresponding pulleys 41, 46.

The sill 12 of the window frame is fashioned in cross section to correspond to the sill of the window, as plainly indicated in Figures 2 and 7, to support the window frame, and in order to hold the window 130

frame against accidental movement the flange 143 of the top cross rail 14 is provided with upwardly extending attaching arms 170 fastened by bolts or other fastening devices 171 to the wall of the building, as plainly shown in Figures 2 and 7. To the side bars 13 are secured weight boxes 180 containing the weights 43 and 48 and provided with vertical separating plates 181 to hold the weights 43 and 48 in each weight box in spaced relation one to the other.

In order to gain access to the weights in the weight boxes 180 the lower portions of the side bars 13 are provided with removable sections 190 (see Figures 1 and 11). The lower ends of the side bars 13 are provided with reinforcing members 195 arranged below the removable sections 190 (see Figure 1).

20 In order to insure a proper joint between the building and the outer portion of the window frame use is made of outside staff or scribe moldings 200 of a desired ornamental cross section and fastened at intervals by screws or other fastening devices 201 to spaced brackets 202 attached to the outer faces of the outer stop beads 21 and 29, as plainly indicated in Figures 2, 7 and 8. It will be noticed that by this arrangement the 25 molding 200 can be readily drawn inward by screwing up the screws 201 to insure firm contact with the wall of the window opening to overcome any irregularities that may be in the wall thus insuring the formation of a 30 very tight joint between the molding and the wall of the window opening.

Instead of forming the outside staff or scribe molding of a separate piece, the same may be formed integral with the outer stop bead 21, as indicated in Figure 14, otherwise the construction of the window frame is the same as above described.

Having thus described my invention, I claim as new and desire to secure by Letters 45 Patent:—

1. In a window, a window frame provided with sash guideways having elastic weather cushions, lower and upper sashes mounted to slide in the said guideways, and free suspension means mounted on the said window frame and connected with the said sashes, and wedge means adjacent the end of the said guideways, to cause the sashes when in open position to drop away from the said 50 cushions and to move the sashes in contact with the said cushions on closing the sashes.

2. In a window, a window frame provided with sash guideways having elastic weather cushions, lower and upper sashes mounted to 55 slide in the said guideways, the width of the

latter being pronouncedly in excess to the thickness of the stiles of the said sashes, the said guideways being provided with wedges to move the sashes in one direction on closing the sashes to engage the stiles 65 with the cushions, and a free suspension means mounted on the window frame and connected with the said sashes, the said suspension means moving the sashes in an opposite direction, on opening the sashes to 70 disengage the stiles from the said cushions.

3. In a window, a window frame provided with beads and parting strips having elastic weather cushions, the said beads and parting strips forming sash guideways, a sash mounted to slide in the said guideways and having stiles, the width of the guideways exceeding the thickness of the stiles, and a free suspension means mounted on the said frame and on which the sash is hung to 80 move the said stiles out of engagement with the said cushions on opening the sash, and means on the said window frame and adapted to engage the said stiles on moving the sash into closed position to tightly engage 85 the said stiles with the said cushions.

4. In a window, a window frame provided with inner and outer beads and parting strips having elastic weather cushions, the said beads and parting strips forming sash 90 guideways, upper and lower sashes mounted to slide in the said guideways and having stiles provided with vertical grooves adapted to engage the said cushions, the width of the said guideways being in excess to the thickness of the said stiles, suspension means mounted on the said window frame and on which the sashes are hung to move the stiles 95 out of engagement with the said cushions on opening the sashes, wedges at the lower ends of the inner beads adapted to engage the stiles of the lower sash to move the stiles

thereof into engagement with the said cushions on closing the lower sash, and wedges on the upper ends of the outer beads 100 adapted to engage the stiles of the upper sash to move the stiles thereof into engagement with the said cushions on closing the upper sash.

5. In a window, an upper sash provided at 110 the top rail with a recess, a cushion held in the said recess, and a window frame provided with vertical guideways in which slides the said sash, the said window frame having a top crossbar provided at the under-side with an integral rib adapted to be engaged by the said cushion on closing the upper sash.

SIDNEY U. BARR.
